UNITED STATES PATENT OFFICE.

GEORGE W. BROWN, OF QUINCY, MASSACHUSETTS, ASSIGNOR TO TUBULAR RIVET & STUD CO., OF BOSTON, MASSACHUSETTS, A CORPORATION OF MASSACHUSETTS.

LACING-STUD-SETTING MACHINE.

Application filed November 22, 1923. Serial No. 676,273.

This invention relates to fastener-inserting machines and more especially to those in which pieces of reinforcing material are automatically applied to the work to strengthen the anchorage of the fasteners. For example, United States Letters Patent No. 1,129,030, granted February 16, 1915, on application of E. E. Wakefield, illustrates a machine for setting lacing-hooks in shoe uppers and having automatic means for feeding a strip of reinforcing material and means for cutting the strip into sections so that each section will reinforce the anchorage of a hook in the upper. The present invention is illustrated as embodied in a machine of the type shown in said patent, but is not limited to a machine of that type or to inserting lacing-hooks, and it is to be understood that the expression "fastener-inserting" used through this specification is intended to have a broad meaning.

According to the construction shown in the aforesaid patent, the strip of reinforcing material is fed with the same amplitude of movement as the work, and the individual pieces of reinforcing material into which the strip is cut are necessarily of the same length as the feeding steps imparted to the work. In some cases the feeding steps of the work are only one-half inch long, but when a strip of reinforcing material is cut into sections one-half an inch in length there is not sufficient margin at one side of the fastener (specifically, the left side) to insure secure anchorage of the fastener.

In view of the conditions explained above, an object of the present invention is to provide improved means for feeding a reinforcing strip a suitable distance to fulfill its purpose in the highest degree irrespective of the spacing of the fasteners one from another, so that when, for example, the feeding steps of the work are relatively short the reinforcing strip may be fed to a greater extent and cut into sections longer than the feeding steps of the work.

With the above object in view, a feature of the invention consists in an organization comprising fastener-inserting mechanism, means for feeding the work step by step, means arranged to feed the strip a greater distance than the work is fed, and means arranged to cut the strip into sections longer than the feeding steps of the work. In practice, this results in a series of individual sections the

leading edges and trailing edges of which 55 are lapped one over another.

When the invention is embodied in a machine of the type illustrated in the aforesaid patent a novel feature consists in supplemental means for feeding the reinforcing 60 strip beyond the point to which it is fed with the work.

Other features of the invention are herein-after described and claimed and are illustrated by the accompanying drawings. 65

In the accompanying drawings—

Figure 1 is a front elevation of a lacing hook setting machine to which my improved strip feeding means is attached.

Figure 2 is a sectional elevation showing 70 the initial positions of the parts adjacent to the inserting locality.

Figure 3 is a view similar to Figure 2 but showing the parts advanced to that stage of the cycle at which a section of the reinforcing 75 strip is severed and the materials are punched.

Figure 4 shows a later stage of the cycle, the work and the reinforcing strip having been fed the same distance to the left, the severed section and a fastener having been applied to the work, and the reinforcing strip being about to receive a supplemental feeding movement.

Figure 5 is a perspective view showing how the supplemental strip-feeding means may be 85 mounted on the presser-foot.

Figure 6 is a section on line 6—6 of Figure 5.

Figure 7 is a section showing two specimens of work provided with a lacing-hook and an 90 eyelet respectively and each provided with a section of a reinforcing strip.

Figure 8 is a view of the upper face of a piece of work provided with sections of a reinforcing strip cut and applied according to 95 this invention.

The illustrated fastener-inserting machine is similar in construction and operation to that shown in the patent above referred to. It comprises a reciprocating head 10 arranged to slide horizontally on the guide bars 11 for the purpose of feeding the work 17. This head carries a guide block 12 arranged to slide in the grooves 13 of the presser foot 14.

This guide block 12 is provided with a slot 105 15 through which a reinforcing strip of tape 16 extends and is also provided with apertures 22 through which the tape-engaging

needles or spurs 21 pass when forced into the tape prior to feeding the same.

These needles or spurs are fastened to a bar 23 which is carried by a spindle 18 to move therewith. A knife 20 is also fastened to the member 23 and extends downwardly to engage the left hand face of the block 12 so that when the spindle descends the knife engages and severs a portion 24 of the tape which extends beyond the block. The downward movement of this spindle 18 also causes the punch 19 to punch a hole through the reinforcing strip and through the work 17 lying on the punch-block 45 (see Fig. 3). The presser-foot 14 now rises to release the work so that it may be fed. The head 10 is now moved to the left, whereby the punch feeds the work and the severed section of the strip while the spurs 21 feed the body of the strip to the same extent. The presser-foot is now lowered, the carrier 26 is raised to insert the fastener 25, and the fastener is clenched by the anvil portion 27 of the punch. The punch now rises to the position shown in Fig. 4, thereby disengaging the spurs 21 from the reinforcing strip and raising the knife 20, following which the head 10 returns to its initial position shown in Fig. 2.

Now, when the feeding movement of the punch 19 and of the spurs 21 is short, say one half inch, the leading edge of the strip 16 is advanced only slightly beyond the line in which the punch subsequently descends to punch the next hole, and if the strip remained at the position to which it is fed by the spurs 21, the leading or left-hand edge of the strip would be too close to the hole to provide satisfactory anchorage for the fastener. This difficulty does not arise at the right-hand side of the punch because the severing means is arranged at a sufficient distance from the punch, and so, whatever reinforcing material is sacrificed by shortening the feeding steps of the work is necessarily taken from the left-hand side of the punch.

To obviate the difficulty just explained I have provided auxiliary means for feeding the reinforcing strip beyond the point to which the spurs 21 feed it, thus insuring a sufficient margin of reinforcing material at the left-hand side of each fastener as well as at the right-hand side. The construction of the illustrated means for this purpose is as follows:

A bracket 28 is fixed to the presser foot support 29 and to this bracket is pivoted at 30 a plate 31 having an outwardly-turned end 32 to which end is secured a downwardly-projecting arm 33 having guide eye 34 in its upper end for the tape 16, and its lower end provided with a tension device comprising a leaf spring 35 and a plate 36 arranged to clamp the reinforcing strip 16. The arm 33 is braced by a strut 37 which leads upwardly and then horizontally as at 38 to engage the for-

ward end of the pivoted plate 31. The clamping couple 35, 36 is normally drawn to the left by a spring 39 and arrested by a stop 40 formed on the plate 31 and arranged to engage the under edge of the fixed arm 28.

A member 42 having a vertical slot 44 is fastened by a screw 43 to the head 10 and has a cam portion 41 arranged to act on the upper portion 38 of the strut 37 to retract the clamping couple 35, 36, while the spurs 21 are feeding the reinforcing strip.

In the operation of the machine, when the spindle 18 with its spurs, knife and punch are in down position, as illustrated in Figure 3, the head 10 is moved to the left into the position illustrated in Figure 4, to feed the shoe upper together with the reinforcing strip into position to receive the stud 25, and during this feeding stroke the cam 41 engages the member 38 on the pivot plate 31 and tips this plate with its feeding arm back into the position illustrated by solid lines in Figure 4, causing the clamping couple 35, 36 to slip back along the tape which is at this time held by the spurs 21, as shown in Figure 3. The spurs, knife and punch are now raised to the position illustrated in Figure 4, and as the head with its guide block and mechanism now move to the right the auxiliary feeding arm 33 is released by the cam and returned by the spring 39 to its normal position (broken lines in Fig. 4) to be arrested by the stop 40, and while swinging to this position it imparts a supplemental feeding movement to the reinforcing strip 16. Therefore, when the guide block 12 has reached its initial position (Fig. 2) a length of the reinforcing strip greater than the stroke of the guide block, is projecting beyond the block and is ready to be severed by the next downward movement of the knife 20. The extent of this additional feed of the reinforcing strip may be varied by adjusting the operating member 42 vertically.

I claim:

1. In a fastener-inserting machine, means for feeding an article of work, means for feeding a strip of reinforcing material in the same general direction as, but with greater amplitude than, the feeding movement of said article, means for severing said strip into sections, and means for inserting fasteners through the severed sections and through said article.

2. In a fastener-inserting machine, means for imparting step feeding movements to the work, means for imparting greater step feeding movements to a reinforcing strip in the same direction as the work, means for severing said strip into sections, and means for inserting fasteners through the severed sections of the strip and through the work.

3. In a fastener-inserting machine, mechanism for feeding an article of work, means operated by said mechanism for feeding a strip of reinforcing material a greater dis-

6 tance than the feeding movement of said article, means for severing said strip into sections, and means for inserting fasteners through said sections and through said article.

7 4. In a fastener-inserting machine, mechanism for feeding an article of work step by step, means for feeding a strip of reinforcing material both during and between feeding steps imparted to said article, means for severing said strip into sections, and means for inserting fasteners through said sections and through said article.

8 5. In a fastener-inserting machine, mechanism for feeding an article of work step by step, means for feeding a strip of reinforcing material one distance during the feeding periods of said article, and another distance between said feeding periods, means for severing said strip into sections, and means for inserting fasteners through said sections and through said article.

9 6. In a machine for setting lacing studs in shoe uppers, reciprocating means for feeding a shoe upper, means connected to said feeding means for feeding a strip of reinforcing tape, auxiliary means cooperating with said strip feeding means to assist in advancing the strip a distance greater than the feeding movement 10 of the upper, and means for setting studs into the upper and strip.

10 7. In a machine for setting lacing studs in shoe uppers, reciprocating means for feeding a shoe upper, means connected to said feeding means for feeding a strip of reinforcing tape, a pivotally mounted tape feed arm actuated by said tape feeding means to assist in advancing the strip a distance greater than the feeding movement of the upper, and means 15 for setting studs into the upper and strip.

11 8. In a machine for setting lacing studs in shoe uppers, means for feeding a shoe upper, a spur connected with the feeding means for engaging and advancing a reinforcing strip 20 in unison with the work, a movable strip-gripping device, means for moving said device back for another grip on the strip as the shoe-upper is fed, means for operating said device to advance the strip as the upper feeder returns for another feeding stroke, and means for attaching a portion of the strip to the upper by setting a stud thereinto.

25 9. In a fastener-inserting machine, mechanism arranged to feed an article of work and a reinforcing strip with steps of commensurate length, mechanism arranged to impart supplemental feeding steps to said strip between feeding steps imparted thereto by the first mechanism, means arranged to cut off a section of said strip, and mechanism arranged to apply the severed section of said strip to the work by inserting a fastener through both.

30 10. In a fastener-inserting machine, means arranged to feed the work and a reinforcing

35 strip step by step at the same time, means arranged to move the strip relatively to the work after it has been fed as aforesaid, means arranged to cut off a section of said strip, and mechanism arranged to apply the severed 70 section to the work by inserting a fastener through both.

40 11. In a fastener-inserting machine, means arranged to feed the work and a reinforcing strip step by step at the same time, means arranged to move the strip lengthwise between feeding steps of the work to alter the relation of the strip and the work, means arranged to cut off a section of said strip, and mechanism arranged to apply the severed 75 section to the work by inserting a fastener through both.

45 12. In a fastener-inserting machine, means arranged to feed the work, two means arranged to operate successively to feed a reinforcing strip, means arranged to cut off a section of said strip, and mechanism arranged to insert a fastener through the work and through the severed section of said strip.

50 13. In a fastener-inserting machine, mechanism arranged to impart one feeding movement to the work in each cycle, means arranged to impart two distinct longitudinal movements to a reinforcing strip in each cycle, means for cutting off a section of the reinforcing strip, and mechanism for applying the severed section of the strip to the work by inserting a fastener through both.

55 14. In a fastener-inserting machine, means for imparting step feeding movements to the work, means for imparting a plurality of longitudinal movements to a reinforcing strip for each step of feeding movement imparted to the work, means for severing said strip into sections, and means for applying 100 the severed sections to the work by inserting fasteners through both.

60 15. A fastener-inserting machine comprising means for imparting step feeding movements to the work, means for imparting a plurality of longitudinal movements of unequal length to a reinforcing strip for each step of feeding movement imparted to the work, means for severing the strip into sections, and means for applying the severed 115 sections to the work by inserting fasteners through both.

65 16. A fastener-inserting machine comprising mechanism for feeding the work, tension means for acting on a reinforcing strip, 120 means for feeding the reinforcing strip relatively to said tension means, means for moving said tension means to impart movement to said strip, means for cutting off a section of the strip, and mechanism for applying the severed section to the work by inserting a fastener through both.

70 17. A fastener-inserting machine comprising work-feeding mechanism including a reciprocatory element, means operable by 130

movement of said element in one direction to feed a reinforcing strip, means operable by movement of said element in the opposite direction to move said strip lengthwise, means for cutting off a section of said strip, and mechanism for applying the severed section to the work by inserting a fastener through both.

18. A fastener-inserting machine comprising mechanism for feeding the work, means

arranged to clamp a reinforcing strip, means for feeding said strip relatively to said clamping means, means for moving said clamping means to shift the strip relatively to the work, means for cutting off a section of said strip, and mechanism for applying the severed section to the work by inserting a fastener through both. 15

In testimony whereof I affix my signature.

GEORGE W. BROWN.
